UNITED STATES PATENT OFFICE.

DANIEL A. LOESER, OF SAG HARBOR, NEW YORK, ASSIGNOR TO THE ALVIN MANUFACTURING COMPANY, OF NEW YORK, N. Y.

DESIGN FOR A SPOON, &c.

SPECIFICATION forming part of Design No. 26,822, dated March 30, 1897.

Application filed February 11, 1897. Serial No. 623,011. Term of patent 7 years.

To all whom it may concern:

Be it known that I, DANIEL A. LOESER, a subject of the Emperor of Germany, residing at Sag Harbor, in the county of Suffolk and 5 State of New York, have invented and produced a new and original Design for Spoon or Fork Handles, of which the following is a specification, reference being had to the accompanying drawings, in which—

10 Figure 1 is a view of the obverse side of a spoon, the handle of which has my new design applied thereto, the tines of a fork being shown in dotted lines. Fig. 2 is a view of the reverse side thereof, showing my design applied to the handle.

15 The leading or characteristic feature of my design consists of foliated and scroll-like ornamentation at opposite ends of the handle and also between the ends, as shown, the ornamentation at the outer end of the handle terminating in a scalloped edge.

20 Referring to the drawings, A represents the handle of a fork or spoon, the obverse side of which, as shown in Fig. 1, has my design ap-

plied thereto, consisting of scrolls and foliage 25 B at the outer end thereof, the scrolls and leaf-like ornamentation D at the lower end of the handle, and the scrolls and foliage C between the ends. The obverse side of the handle bears the ornamentation E at the outer 30 end, the ornamentation F at the inner end, and the scrolls G between the ends, the outer end of the handle terminating in the scalloped edge H.

What I claim is—

35 1. The design for the handle of a spoon or fork as set forth.

2. In the design for the handle of a spoon or fork, the design of the obverse side of the handle, as set forth.

40 3. In the design of the handle of a spoon or fork, the design of the reverse side of the handle, as set forth.

DANIEL A. LOESER.
